DAM

Theodor Becher, Wiesbaden, Germany, assignor
to Maschinenfabrik Augsburg-Nürnberg A. G.,
Nuremberg, Germany, a corporation of Germany

Application September 18, 1935, Serial No. 41,079
In Germany September 27, 1934

3 Claims. (Cl. 61—25)

As closing means for weirs, often times flaps are used which are hinged to the bottom of the weir and permit the passage of a smaller or larger amount of water, according as the flap has been 5 lifted more or less.

Particularly favorable in many respects are the so-called fish-belly flaps which require a drive at only one end thereof by reason of their torsional strength and are suited for weirs of considerable length.

Mounting such flaps upon stationary weirs or upon dam walls, the top or crest of which is disposed at a considerable height above the bottom of the weirs, is not connected with difficulties, but 15 matters are otherwise if the axle of the flap is located near the bottom of the weir, as in this case a cavity must be provided which receives the flap, in order to prevent hindrance of navigation, discharge of high water, and the like.

20 Sand, shingle and the like collect in said cavities and may give trouble to the proper service of the weir.

Similar as with the above-mentioned fish-belly types of flaps are other matters with some other 25 constructional forms of flaps, mention of which can be omitted.

It is known to remove the shingle, mud, and the like by means of scavenging.

The present invention relates to improved constructional form operating with scavenging, and 30 the gist of the invention resides in that a slot extending across the entire breadth of the river, etc., and communicating at its upper side with the head water and terminating at its lower side 35 into a bottom cavity is provided, whereby the possibility is presented to conduct water from said slot into said cavity, in order to scavenge away the shingle etc. The said slot may commence directly at the head water side of the bottom of the 40 weir, or a separate channel may be provided which communicates with the head water. Shutting-off members may also be provided for regulating the amount of the scavenging water. It is suited to the purpose in view to positively actuate the 45 respective member from the flap of the weir, so that at certain distinct positions of the flap the scavenging commences or ceases automatically, as the case may be.

In the accompanying drawings:—

50 Figure 1 is a vertical transverse section of a weir and flap associated therewith showing one form of the invention, the flap being shown in raised position;

55 Fig. 2 is a view of the structure shown in Fig. 1, showing the flap in its lowered position;

Fig. 3 is a section of a portion of a weir and flap, showing another form of the invention, the flap being shown in raised position;

Fig. 4 is a view of the structure shown in Fig. 3, showing the flap in its lowered position;

Fig. 5 is a view similar to Fig. 3, illustrating another form of the invention;

Fig. 6 is a view similar to Fig. 4 of the structure shown in Fig. 5.

Fig. 7 is a view similar to Fig. 3 of a third modified form of the invention; and

Fig. 8 is a view similar to Fig. 4 of the structure shown in Fig. 7.

Referring to Figs. 1 and 2, *a* denotes the flap which resembles, in transverse section, a fish's-belly and is hinged to the bottom *k* of the weir at the head water side of the same. The flap is shown in two positions, viz. in full lines and in dotted lines. In the first of these positions the flap is in its highest position, whereas the other position indicates the normal position of the flap.

A passage *i* is formed in the weir and extends from the bottom *k* to the bottom of the cavity *b*.

A slide *l* is provided at the entrance end of the passage *i*, and said slide is connected with 25 the flap *a*, by means of a link *m*.

An aperture is formed in the slide *l* through which head water can flow into the passage *i* when the flap is in its highest position, as shown by the full lines, Fig. 1. In the normal position 30 of the flap *a* (position *a''* Fig. 1) and in any other lower position of the flap, even in its lowermost position (position *a'*, Fig. 2), the position of the slide *l* is such that the entrance to passage *i* is closed.

In the form of the invention shown in Figs. 3 and 4, the scavenging passage *n* is by far shorter than the passage *i* shown in Figs. 1 and 2, and the closing slide *o* is located nearer to the flap *a*.

Counter, however, to the form of the invention shown in Figs. 1 and 2, the passage *n* is closed by the slide *o* when the flap *a* is in its highest position (Fig. 3) and said slide is open when the flap is in its lower or lowermost position (Fig. 4), so that the shingles, etc., are driven away by the 45 water rushing down through the slotted member or grating *s* (Fig. 4) into the main current and are at once carried away by the same.

In the form of the invention shown in Figs. 5 and 6, the flap *q* has a downwardly projecting extension *r* which closes the discharge slot *p* when the flap is in its lower or lowermost position, as in Fig. 6, whereas otherwise (Fig. 5) said slot is open so that the scavenging water can rush down into the cavity *b*. At the upper portion of the 55

slot p there is a stationary slotted grating s' which is mounted on the stationary dam structure and projects outwardly towards the flap q . When the flap q is in raised position (Fig. 5) and 5 the entrance to the slot p open, the grating s' is adapted to function as a screen for preventing large particles of foreign matter from passing down into the cavity b . When the flap is lowered (Fig. 6) the extension r engages the bottom 10 of the grating s' , thereby cutting off communication through the slot p .

In Figs. 7 and 8, the arrangement and combination of the parts is the reverse of those shown in Figs. 5 and 6, in that the extension r' keeps 15 the discharge or scavenging slot p' closed when the flap q' is in its upper position (Fig. 7) and is open when the flap q' is in its lower position, as in Fig. 8. Mounted on the dam at a point out 20 of the way of the swinging extension r' and adjacent to the entrance to the slot p' , is a grating or the like, s'' .

The member designated by s , s' and s'' in all of 25 the views is a screen or rake-like grating by which shingle, etc. that has been carried along the bottom of the river is prevented from passing down into the cavity b . In the constructional forms of the invention shown in Figs. 1 to 4 inclusive the member s constitutes a separate member arranged in front of the discharge or 30 scavenging slot and operatively connected with the flap so as to move therewith. In the forms of the invention shown in Figs. 5 to 8 inclusive, the grating is stationary and projects outwardly from the main dam structure.

35 I claim:

1. The combination with a main dam structure having an upper portion and a lower portion formed on the bed of a stream, with a wall connecting both portions, the lower portion being disposed downstream with respect to the upper portion of the dam structure and forming a cavity extending across the bed of the stream at the rear or downstream side of said wall, of 40 a movable flap hingedly connected along one edge to the upper portion of the dam structure adjacent to said wall, said flap being adapted to normally project upwardly from the upper por- 45

tion of the main dam structure to dam up the water in the stream and being adapted when swung downwardly to be disposed within the cavity on the downstream side of said wall, a passage formed in the dam structure and connecting the pool on the upstream side of said flap with the cavity, and means operatively connected to said flap and mounted in the dam structure at the entrance to said passage for controlling communication through the passage. 10

2. A dam comprising an upper portion and a lower portion formed on the bed of a stream, a wall connecting both portions, the lower portion being disposed downstream with respect to the upper portion and constituting a cavity extending across the bed of the stream at the rear or downstream side of said wall, a movable flap hingedly connected along one edge to the upper portion of the dam adjacent to said wall, said flap being adapted when swung downwardly to be disposed within said cavity, a slot formed in the dam on the upstream side of said flap, said slot being coextensive with said flap through which water can flow into said cavity from the head water, a slide coextensive with said slot and disposed at the entrance to said slot for controlling communication therethrough, and means operatively connecting said slide with said flap for actuating said slide in accordance with the relative position of said flap. 20

3. A dam comprising an upper portion and a lower portion, a wall connecting both portions, the lower portion being disposed downstream with respect to the upper portion and constituting a cavity extending across the dam at the rear or downstream side of said wall, a movable flap hingedly connected to the dam adjacent said wall, said flap being adapted when swung downwardly to be disposed within said cavity, a passage coextensive with said flap and located between the flap and the dam through which water can flow into said cavity from the head water, and means operatively connected to said flap and disposed at the entrance to said passage for controlling communication through the 40 45
